PRESSURE APPLICATOR FOR FLOWABLE MATERIAL

Arthur Kraszeski, Newburgh, N.Y., assignor to Alpha Research Corp., New York, N.Y., a corporation of New York

Filed Aug. 3, 1964, Ser. No. 386,840
6 Claims. (Cl. 112—2)

This invention relates to adhesive applicator attachments securable to the frame of a sewing machine, and especially to that type in which the adhesive is forced through an applicator nozzle automatically on to such a point of the work that the needle cannot pass through the adhesive.

The invention is directed to the provision of a simple inexpensive readily attachable adjustable easily controlled and compact device for applying auxiliary adhesive as required to various types of seams in textiles or other flexible sheet materials during the sewing operation and to supplement the stitching, thereby to meet extraordinary conditions, or for special purposes some of which are described in more detail hereinafter.

The invention is further directed to the provision of simple and efficient means for controlling the size, shape and position of the stream of emitted adhesive and for fully synchronizing the deposit of adhesive with the acceleration, deceleration and stoppage of the sewing operation and for cutting off the stream while sewing without otherwise interfering with the operation of the attachment.

The invention is further directed to the provision of means for applying adhesive in any desired direction to a selected point or area of the sheets to be stitched together, simultaneously with the sewing thereof and with or without the folding of a binding tape about the marginal portions of the sheets.

The various objects of the invention will be clear from the description which follows and from the drawings, in which

FIG. 1 is a fragmentary elevational view with parts in section of a typical sewing machine frame and of the attachment in the operative position thereof.

FIG. 2 is a vertical sectional view of the main part of the attachment taken in part on the broken line 2—2 of FIG. 3, showing also one form of the swingable and adjustable nozzle.

FIG. 3 is in part a horizontal section view taken on the line 3—3 of FIG. 2 and in part a bottom plan view of the gear pump and extruding worm.

FIG. 4 is a vertical sectional view of a modified form of the combined nozzle and nozzle holder.

FIG. 5 is a fragmentary elevational view partly in section of another modified form of the nozzle and holder showing the adhesive applied between two sheets.

FIG. 6 is a top plan view of FIG. 5 partly broken away and showing binding tape being applied to the edges of the sheets being stitched.

It is intended that the single shaft of the attachment be driven from and in timed relation to any suitable part of the sewing machine 10, whereby the same amount of adhesive is deposited on each unit length of the work during the feed of the work during the sewing operation regardless of the speed of such operation. In the form shown in FIG. 1, a convenient drive may consist of a gear wheel as 11 on the main shaft 12 of the sewing machine, suitably engaged with a gear wheel 13 of any suitable type of reduction gearing designated generally by the numeral 14. Obviously however, the reduction gearing 14 may be driven through a suitable friction wheel from the usual hand wheel or pulley, not shown, forming part of the conventional sewing machine. From

2

said gearing, suitable connections such as the universal joints 15 and 16 and the bevel gears 17 and 18 continuously rotate the single shaft 19 (FIGS. 2 and 3) of the attachment at the required speed. If desired, the shaft 5 may be driven by means of a suitable flexible shaft from a selected moving part, not shown, of the sewing machine.

A container 20 for adhesive or other suitable material of the required viscosity such as sealing plastic, which will be referred to hereinafter as "adhesive," is supported on the frame of the machine as by the bracket 21 or otherwise supported or hung in a convenient place near the machine. From the container, the adhesive flows through the flexible tube 22 to the gear pump 23 of the attachment, where the adhesive is subjected to the 10 desired pressure.

In order to insure the measured uniform and forcible delivery of adhesive to the work at all times and regardless of the viscosity of the adhesive, the pump 23 delivers the adhesive to and cooperates with the extruder feed 15 worm or screw 24 whereby the flow volume depends solely on the circumferential speed of the coaxially mounted and fixed together extruder work 24 and the pump gear wheel 23a, said speed in turn depending on the speed of the sewing operation. Driven by the gear wheel 23a is the second idle pump gear wheel 23b on a short stud shaft 23c which has its bearing in the upper section 25 of the pump casing. Both gear wheels 23a and 23b are housed in the pump chamber 26 of the casing section 25. A substantial part of the circumference of each gear wheel fits the wall of the pump chamber closely and exactly so that even an adhesive of low viscosity cannot pass the gear wheel unless said wheels are in motion.

The pump chamber 26 communicates with the nipple 27 for flexible hose 22 and receives the adhesive from the container 20. The lower section 28 of the pump casing closes the bottom of the chamber and has a flat top surface 29 cooperating with the flat bottom surface 30 of the upper section 25 to form a leak proof closure for the chamber. Extending longitudinally through the section 28 is the downwardly and inwardly tapering passage 31 for adhesive. The extruder worm 24 is fitted closely and exactly to said passage to rotate therein in engagement with the wall thereof and serves in cooperation with the gear wheel 23a, with which it is in tandem, to feed a metered quantity of adhesive therethrough on each rotation of the shaft 19 from which the worm extends. An important feature of this construction is the self cleaning action of the pump and extruder worm in the attachment. The edges of the gear wheels are of the worm during the rotation thereof scrape off any adhesive which may have hardened on the walls of the pump chamber and passage 31 adjacent thereto during a period of non-use of the attachment, whereby the necessity for disassembling the parts for cleaning purposes on such occasions is eliminated. Because of the self cleaning characteristic of the pump and extruder mechanism, it becomes possible to use effectively a quick drying adhesive when desired without adversely affecting the operation of the attachment.

60 Connecting the pump chamber with the passage 31 is the inclined hole 32 through which the pump forces the adhesive under pressure. Suitable screws as 33 hold the sections 25 and 28 removably together for assembly, cleaning and repair purposes.

65 As has been indicated, special conditions may require the use of adhesive of various characteristics in clothing, bags, upholstery, cushions and similar articles which are usually stitched. For example, open mesh fabrics do not hold stitching well enough to take the wear to which they are subjected when used in automobile ventilated seat cushions so that provision has previously been made to supply adhesive to the stitching to reinforce it, and to the 70

binding tape customarily used at the edges of the cushion, without having the needle pass through the line of adhesive. Similarly, where strong leak proof bags are required for such pulverant materials as flour and cement, reinforcement of the stitching against leakage therethrough is desirable. Certain types of clothing such as inflatable suits, or clothing where extraordinary strength is required, are well adapted for the reinforcement of the stitching thereof. Upholstery of woven plastic may well have adhesive reinforced seams and the open edges of inflatable fabrics may well be finished with auxiliary adhesive.

Means have therefore been provided herein whereby the stream of adhesive may be directed to the exact point where it is required to supplement the stitching, in the quantity desired and in the shape of the stream required for the most effective results. For such purposes, the attachment is intended to operate with various types of interchangeable nozzles such as are illustrated for example, in FIGS. 2 and 4-6. As best seen in FIG. 2, the elongated neck 35 of the pump section 29 is internally threaded at the lower end thereof to receive the combined nozzle adaptor and male valve member 36. The adaptor is provided with the adhesive passage 37 coaxial with and forming a continuation of the passage 31. The male needle valve member 38 projects from the bottom of the adaptor 36 coaxially of the passages 37 and 31, the adhesive being discharged from the passage 37 around the member 38 through the inclined holes 39 under the urge of the extruder worm. In that form of the nozzle shown in FIG. 2, the female needle valve member 40 is internally threaded at its upper part to receive adjustably the lower end of the male valve member 38 and is also threaded externally at its lower end for the reception of the rotatable nozzle holder 41. The flexible O-ring 42 seals the lower end of the threaded connection therebetween while permitting limited rotational movement of the holder 41. The stop pin 43 projecting from the member 40 and inserted into a suitable recess 44 of limited circumferential extent, limits the swinging movement of said holder relatively to the member 40 in either direction.

The triple threaded connection between the various parts permits the stream of adhesive to be cut off completely when desired by the rotation of the member 40 in the proper direction to move the top of the passage 45 therein firmly against the valve member 38. The stitching operation may, nevertheless, proceed for a limited time while the valve is closed. While some heat is developed during the agitation of the adhesive by the pump and worm without advancing the adhesive, the amount of heat so produced in relatively short spurts is negligible. Obviously, the adhesive may be cut off in other ways, as for example, by disconnecting the drive to the pump by the interposition of a suitable clutch or other disconnecting device in such drive. Or the cut-off may be accomplished by providing between the outlet port 32 of the pump chamber and the inlet port 27, a spring loaded by-pass valve to circulate the adhesive therebetween under the pump pressure when the needle valve is closed, in a manner which is now well understood and needs no further description nor illustration.

As will now be apparent, the member 40 can be adjusted with respect to the relatively fixed adaptor 36 to completely or partly open the needle valve and thereby to control the quantity of adhesive in the stream. To maintain the part 40 in the properly adjusted position thereof, a set screw 46 is provided passing through the flange at the upper end of the member 40 and into contact with the adaptor 36. The pointer 43 on the neck 35 cooperates with the indicating markings or scale 49 (FIG. 6) on the top surface of the member 40 to indicate to the user the effective size of the needle valve opening and the consequent quantity of adhesive being delivered. After such effective size of the needle valve passage has been thus determined and set, the nozzle holder 41 may be rotated into the desired position relatively to the member 40.

The rigid straight tubular nozzle 50 (FIG. 2) which can be used to apply adhesive between two sheets, is removably held in the hole 51 of the holder 41 by means of a suitable set screw 52 and has a hole therein communicating with the passage for adhesive in said holder. Said nozzle is of the desired length to arrange the discharge opening thereof at the proper point of the seam to be stitched and thereby to deposit the discharge end of the stream of adhesive in the proper position to clear the needle of the sewing machine. A handle 53 having a screw thread connection with the end of the nozzle tube remote from the discharge end and having an elongated pin extension 54 is provided for manipulation of the nozzle by the rotation thereof as far as is permitted by the pin 43, the handle being used to withdraw the nozzle from the seam when the stitching is to be done without adhesive, the O-ring permitting such rotation of the nozzle and the holder 41 without breaking the seal.

In the form shown in FIG. 4, the female valve member 140 terminates at its lower end directly in the tapered nozzle 55 adapted to deposit adhesive on the top of a sheet such as one of open mesh fabric wherein the adhesive can pass through the openings in the mesh on to a second sheet or on to a binding tape or both.

Referring to FIG. 5, the nozzle holder 241 is shaped at its lower end into the nipple 56 for holding the flexible nozzle 57 of plastic or other suitable material and shown as having the end portion thereof bent to assume a horizontal position wherein it is inserted between two sheets 58 and 59 of fabric. As shown, the discharge opening is positioned outwardly of the sewing needle 60 so that the innermost part of the stream of adhesive clears the needle. After the adhesive passes the needle, the presser foot 61 of the sewing machine may flatten the adhesive and spread it into the stitching 62 (FIG. 6). In the form shown, the nozzle end is flattened to provide a substantially rectangular discharge opening producing a relatively wide and thin stream 63 of adhesive. The angle which the nozzle makes with the line of stitching or feed of the work also affects the width of the strip or stream of adhesive deposited and may be varied to the extent permitted by the stop pin 43. For ease in adjusting the angular position of the nozzle, whether in an operative or inoperative position, a metal strip as 64 is secured to the nozzle as by means of the sleeve or loop 65 and may have a pivot pin as 66 thereon arranged coaxially of the extruder worm and entering a suitable opening in the sewing machine table. By swinging the handle loop at the end of the strip 64 about said pin, the nozzle may be withdrawn from the seam or adjusted at the desired distance from the stitching and the effective width of the deposited strip of adhesive adjusted.

In FIG. 6 is shown the edge binding tape 67 being folded around the marginal portions of the sheets in a known manner, the tape being folded over the strip of adhesive deposited between said sheets, it being understood that the end of the nozzle may be arranged wherever desired, and that a bifurcated nozzle would be used should it be required that the adhesive be placed simultaneously on two different surfaces of the sheets.

It will now be seen that there has been provided an extremely compact, efficient and relatively inexpensive attachment small enough for placement on the frame of a typical sewing machine, adapted to deposit adhesive where and in the shape desired, having interchangeable nozzles for that purpose, adapted to control the size of the adhesive strip deposited and to cut off such deposit and otherwise to attain adequately the various objects of the invention.

While certain specific forms of the invention have herein been shown and described, various obvious changes may well be made therein without departing from the spirit of the invention defined by the appended claims.

I claim:

1. An adhesive applicator for attachment to a sewing machine comprising

a feed worm and
a gear wheel arranged on a common axis for rotation
as a unit,
the gear wheel being part of a pump feeding adhesive
to the worm,

a nozzle adaptor having an axis coaxial with the com-
mon axis and receiving the end portion of the worm
and terminating in a needle valve,

nozzle means communicating with the valve, and
mounting means detachably mounting said nozzle
means on said adaptor.

2. The applicator of claim 1, the nozzle means includ-
ing

a nozzle, and
means adjustable relatively to the adaptor for supporting
the nozzle.

3. The applicator of claim 2, the nozzle being of flexi-
ble plastic material adapted to pivot about the common
axis of the adaptor, the worm and the gear wheel.

4. An applicator for adhesive material comprising
a gear pump having an upper casing section and a
lower casing section closing the bottom of the upper
section, there being a pump chamber between the
sections,

means for conducting flowable material to said cham-
ber,
a shaft,

5

10

15

20

25

an extension on said shaft passing through said upper
casing section,

means for driving said shaft, said gear pump comprising

a gear wheel fixed on said extension,

a feed worm constituting part of said extension and
passing through said lower section, and

a nozzle for receiving said material from the worm.

5. The applicator of claim 4, and nozzle mounting
means for adjusting the nozzle toward and from the worm
and around the axis of the worm as a pivot.

6. The applicator of claim 5, the nozzle being flexible
and having a rectangular and relatively thin and wide dis-
charge opening.
